**DISPLAY MANIKIN AND SUPPORT
 MEANS THEREFOR**
 William P. Yerger, 797 K St., Monroe, La.
 Filed Apr. 23, 1963, Ser. No. 275,066
 3 Claims. (Cl. 223—120)

This invention relates to improved support means for manikins and in particular to support means for manikins that resemble conventional shoes and which will not interfere with dressing, undressing, or the arrangement of clothing on the supported manikins.

It is a principal object of the present invention to provide foot engaging rigid support means resembling shoes for a manikin whereby the sole support for the manikin is through the feet of the manikin, eliminating all need for independent support rods, support wires and the like which are conventionally employed with clothing manikins.

In general, manikins have been supported by rigid rods, the lower ends of which engage extended surface floor supported platforms while the upper ends are releasably secured to a body portion of the manikins. Such support rods interfere with dressing and undressing of manikins and the arrangement of clothes about the lower extremities of the manikins. In some instances, these conventional support rods prevent the placement of certain clothes on manikins without damage to the clothes rendering them useless for sale to the public. For example, manikins employing conventional rod support means may not conveniently be dressed in capri pants, slacks, leotards, pedal pushers and the like.

A further object of the present invention is to provide support means for a clothing manikin which may be contoured to resemble the current shoe fashion and the color of the support means may be readily changed to match the particular clothing ensemble in which the manikin is dressed.

These and other objects and advantages are provided by support means for a clothing display manikin comprising a pair of rigid members shaped to conform to the shape of the feet of a manikin and contoured to resemble a left and a right shoe, each of said rigid members having a supporting surface engaging portion resembling the sole and heel of a shoe and an upper portion resembling the top of a shoe, a base member having an extended planar floor engaging surface, tie means releasably connecting the supporting surface engaging portion of each of the rigid members to said base member and further tie means releasably connecting the feet of a manikin to the heel section of the upper portion of the rigid member.

The invention will be more particularly described with reference to the illustrated embodiments of the invention shown in the accompanying drawings wherein:

FIG. 1 is a perspective view of a clothing display manikin having the novel support means of the present invention;

FIG. 2 is a fragmentary rear view of the structures shown in FIG. 1;

FIG. 3 is a fragmentary top plan view of an embodiment of the support means of the invention;

FIG. 4 is a fragmentary sectional view substantially on line 4—4 of FIG. 3; and

FIG. 5 is a fragmentary vertical sectional view through one of the support means and leg of the clothing display manikin shown in FIGS. 1 and 2.

Referring to the drawings and in particular to FIGS. 1 and 2, there is illustrated a clothing display manikin generally designated 10 which includes a body portion 12, a head portion 14, left and right arms 16 and 18 and left and right legs 20 and 22. The illustrated manikin is

2

of the type wherein the legs 20 and 22 are formed integrally with the lower portion of the body 12 and the legs are positioned in an aesthetic relationship to the body whereby the heel of leg 22 is closer to the floor than the heel of leg 20 as more clearly illustrated in FIG. 2 of the drawings. Thus, without the support means of the invention with the body of the manikin in a generally vertical position, only the toe portions of each of the feet would engage a planar horizontally directed surface.

The improved support means of the invention generally comprise a pair of rigid members 26 and 28. The internal surfaces 30 and 32 of rigid members 26 and 28, respectively, are shaped to conform to the shape of the cooperating feet of the manikin to be supported. The external surfaces 34 and 36 of each of the rigid members 26 and 28, respectively, are contoured to resemble a left and a right shoe. The external configuration of each of the pair of members thus includes a sole 20 resembling portion 38, a heel resembling portion 40, a toe resembling portion 42, a counter resembling portion 44 and a vamp resembling portion 46. The particular configuration of the external shoe resembling portions of the support members may be widely varied to suit the current fashion trends. Further, as will be particularly apparent from FIG. 2 of the drawings, while each of the pair of rigid support members 26 and 28 is of similar external configuration, each member is contoured to provide at least heel and sole support for its cooperating foot. Thus, it will be noted that heel 40 of support member 26 is longer than heel member 40 of support member 28, thus providing spaced zones of contact between each of the pair of rigid members 26 and 28 and a cooperating base member generally designated 50.

Base member 50 is illustrated as comprising a square plate member having a lower planar surface 52 adapted to be supported from a floor or the like and a generally planar upper surface 54 adapted to releasably receive the pair of rigid support members.

The base member 50 is preferably constructed of sheet metal and in the illustrated form of the invention, the base member is square when viewed in plan and is approximately 24 inches on a side. The base member 50 is detachably secured to the display manikin support means 26 and 28. In the illustrated form of the invention, the securing means comprise bolts 56 which pass through bores 58 in the base member 50 and engage threaded openings 60 in the sole resembling portion of each of the support members 26 and 28.

A further bolt member 62 passes through a bore 64 in the base member 50 and is received in a threaded bore 66 in the heel resembling portion of each of the support members.

In the illustrated form of the invention, the support members 26 and 28 are molded from a rigid plastic composition, and particularly satisfactory results have been obtained with plastic reinforced with fiber glass cloth. To insure lasting cooperation between the bolts 56 and the support members, the support members are formed or molded with inlaid or integral metal plates 68 and 70. Plate 68 is provided with a flat platform engaging surface 72 and upturned wing portions 74 which follow the contour of the vamp resembling portions 46 of each of the support members to provide additional strength and rigidity to the support members.

The plate member 70 is illustrated as an inlaid square at the forward end of the toe portion of the sole resembling section of each of the support members.

Where the support members are cast or formed from metal such as brass, aluminum, die casting zinc and the like, the inlaid metal plates 68 and 70 are not required.

The assembly further includes releasable means inter-

connecting each foot of the clothing display manikin and its rigid formed support member. In the illustrated form of the invention, the attaching means comprise bolts 76 which pass through bores in the heel resembling section of the upper portion of the support members. A co-operating threaded bore 78, as illustrated in FIG. 5, is provided in the feet of the manikin.

From the foregoing description, it will be seen that support means are provided for a clothing display manikin which is artistic and functional and eliminates the conventional rod supports which interfere with dressing, undressing and the fit of clothing on display. Further, as hereinbefore indicated, the color of the support means may be readily changed by spray coating the support members in a color to match or contrast with the particular displayed clothing. Further, where the particular design of the support members goes out of style, new support members may be readily constructed to keep the manikin in the current style.

I claim:

1. In combination a display manikin resembling in size and configuration a human being, said manikin including at least a body portion, depending legs rigidly attached thereto, feet for said legs, and support means therefor, said support means comprising a pair of rigid plastic members shaped to conform to the shape of the feet of the manikin and contoured to resemble a left and a right shoe, each of said rigid members having a supporting surface engaging portion resembling the sole and the heel of a shoe and an upper portion resembling the top of a shoe, a base member having an extended planar floor engaging surface, tie means rigidly and releasably connecting the supporting surface engaging portion of each of the rigid members to said base member, and further tie means rigidly and releasably connecting the feet of

the manikin to the heel section of the upper portion of the rigid member.

2. The invention defined in claim 1 wherein said tie means and said further tie means comprise bolts.

3. In combination a display manikin resembling in size and configuration a human being, said manikin including at least a body portion, depending legs rigidly attached thereto, feet for said legs, and support means therefor, said support means comprising a pair of rigid plastic members shaped to conform to the shape of the feet of the manikin and contoured to resemble a left and a right shoe, each of said rigid members having a supporting surface engaging portion resembling the sole and heel of a shoe and an upper portion resembling the top of a shoe, a base member having an extended planar floor engaging surface, metal plates inserted in each of the pair of rigid members in the shoe sole resembling portion, threaded openings in said metal plates, cooperating bores in the base member, and threaded bolts passing through the openings in the base member and engaging the threaded openings in the metal plates for rigidly and releasably connecting the supporting surface engaging portion of each of the rigid members to said base member, and further threaded connectors rigidly and releasably attaching the foot of the manikin to the heel section of the upper portion of the rigid members.
